CART JACK WITH CLAMPING PLATES
ADAPTED TO ADOPT AN INCLINED POSITION RELATIVE TO THE RAMEugen Braselmann, Delle, near Breckerfeld,
GermanyApplication January 8, 1932, Serial No. 585,579
In Germany January 15, 1931

2 Claims. (Cl. 254—106)

I have filed application in Germany on January 15, 1931.

This invention relates to a cart jack, the ram of which is lifted and held by two plates adapted to adopt an inclined position relative to the ram, one of said plates adapted to be lifted by means of a lifting cam or lever and the other being unable to follow the cam movement and serving as holding device. These clamping plates are so recessed, that an imaginary line between their outermost clamping points extends substantially perpendicular to the axis of the ram.

According to the invention the clamping plates are flat plates, and the aperture for the passage of the ram is cut out on the diametrically opposite points of the upper side and lower side to such a distance, that the connecting lines of the outermost clamping points thus formed are again approximately perpendicular to the axis of the ram. Thus, it is possible to give to the curved ends of the cut out portions or extensions of the ram passage hole any desired steep inclination to the axis of the ram, and consequently the clamping effect on the ram in the curved ends of the diametrical cut out portions, caused by the recessing of the clamping plates and occurring on both sides of the imaginary line connecting the two outermost clamping points, can be increased so that the clamping plates, in assuming an inclined position, wedge more rapidly and reliably against the ram.

An embodiment of the invention is illustrated by way of example in the accompanying drawing, in which:—

Fig. 1 shows in side elevation partly in section a jack fitted with the improved clamping plates.

Fig. 2 is a longitudinal section of the jack taken at right angles to Fig. 1.

Fig. 3 shows a clamping plate in side elevation partly in section.

Fig. 4 is a top plan view of Fig. 3.

The ram 1 of the jack is guided in an upright 2. A clamping plate 3, adapted to assume an inclined position relative to the ram, is adapted 45 to be lifted by a cam 4 actuated by means of a hand lever, and lifts the ram but, in descending, slides idly over the surface of the ram. The holding of the raised ram is effected by a second clamping plate 5, which is mounted at one side 50 in the upright of the jack. By lifting this clamping plate 5 the ram 1 is lowered.

The clamping plates 3 and 5, as shown in Figs. 3 and 4, are cut out on their upper and lower sides at diagrammatically opposite points so that 55 the two cut out portions together have approximately the height of the clamping plate. The cut out portions may also be of different depths. Consequently the imaginary line between the outermost clamping points *a* and *b* of the plates 60 is approximately perpendicular to the longitu-

dinal axis of the ram. These cut out portions extend into the passage aperture of each clamping plate on the lines *c* and *d*, which are inclined to the axis of the ram. These lines *c* and *d* correspond to a bend in the clamping plate but, according to the construction illustrated in Figs. 3 and 4, they can extend steeper than in a reclosed clamping plate. By the term "reclosed clamping plate" is meant a plate with a bent or crank-like formation similar to that shown in applicant's Patent No. 1,824,768 granted Sept. 19, 1931. As the clamping plate assumes an inclined position, during which it oscillates around the outermost clamping point *a* or *b*, the lateral clamping of the ram on the curved lines *c* and *d* is increased as desired, independently of the position of the outermost clamping points *a* and *b*.

I claim:—

1. A vehicle jack having a base member provided with a vertical opening, a ram vertically movable in said opening, a flat latch plate having an opening through which said ram passes, means for supporting said plate at one edge to permit the plate to tilt with the supporting means as a fulcrum, the said plate having its upper surface beveled downwardly to said opening on the side of the ram adjacent the supporting means and having its under surface beveled upwardly to the opening on the opposite side of the ram, a similar flat operating plate provided with an opening through which the ram passes and having similar beveled surfaces, and an operating lever pivoted to the base member and engaging beneath that side of the operating plate having its upper surface beveled, the surfaces of the openings opposite the bevels being segmento-cylindrical.

2. A vehicle jack having a base member provided with a vertical opening, a ram vertically movable in said opening, a flat latch plate having an opening through which said ram passes, means for supporting said plate at one edge to permit the plate to tilt with the supporting means as a fulcrum, the said plate having its upper surface beveled downwardly to said opening on the side of the ram adjacent the supporting means and having its under surface beveled upwardly to the opening on the opposite side of the ram, a similar flat operating plate provided with an opening through which the ram passes and having similar beveled surfaces, and an operating lever pivoted to the base member and engaging beneath that side of the operating plate having its upper surface beveled, the surfaces of the openings opposite the bevels being segmento-cylindrical, said beveled surfaces each extending substantially half way around said ram and each bevel gradually increasing in depth from its ends to its middle portion and the beveled surfaces of each plate being parallel to each other.

EUGEN BRASELMANN. 120
